UNITED STATES PATENT OFFICE.

WILSON R. MYERS AND BERNHARD O. OPITZ, OF PORTLAND, OREGON.

DEPOSITING APPARATUS.

Original application filed December 7, 1926, Serial No. 153,099, and in Canada December 24, 1926.
Divided and this application filed July 18, 1927. Serial No. 206,665.

Our invention relates generally to the confectioner's art and it particularly has for its objects to provide a simple, effective apparatus to deposit the materials employed in measured quantities; second, to provide an apparatus of the kind referred to in which the moving parts which come in contact with the materials to be deposited may be cleaned without disassembling the apparatus; and third, to provide a compact simple mechanism for operating the piston and sleeve valve from a single constantly rotating shaft with easily accessible provision for adjusting the stroke of the piston to vary the charge of the material.

This application is a division of our application Serial No. 153,099, filed December 7, 1926.

The invention claimed herein resides in the novel combination, design and arrangement of parts which will hereinafter be described and pointed out in the appended claims, reference being had to the accompanying drawing, in which:

Figure 1 is a perspective view including a section taken through the ejecting cylinders.

Figure 2 is a diagrammatic section through a material handling cylinder showing parts at the completion of a loading.

Figure 3 shows the same parts in position to admit material to the measuring compartment.

Figure 4 shows the same parts with the measuring compartment completely filled.

Figure 5 shows the same parts with the intake port of the measuring compartment closed and the discharge port opened from which a definite quantity of material is discharged.

In the drawing which illustrates our invention as designed for use in the machine disclosed in our application aforesaid, 47 indicates a hopper which is provided with a jacket 48 that is supplied with a suitable heating or cooling substance (accordingly as the content of the hopper is one requiring the application of heat or cold to maintain its fluidity) by a pipe 49. In the base 50 of the hopper 47 are formed a plurality of material measuring pockets 51, preferably in the form of cylinders, in each of which is slidably placed a sleeve 52. Each sleeve 52 has an inlet port 53 which registers with the opening 54 in the bottom of the hopper 47 when the sleeve is in its outermost position. Each

sleeve 52 is also provided with an outlet port 55 which registers with the port 56 in the base 50 when the sleeve 52 is in its innermost position. All of the sleeves 52 are joined by the common head 57 to which movement is imparted by the levers 58 which pivot on the rod 59, and each of which levers is provided with two cam lobes 60 between which can operate the cams 61 on the shaft 62, which is driven by any suitable means. The shaft 62 passes through a slot 66 in each of the levers 58 which allows them to be moved by the cam 61.

The rod 59 is supported by the side frames 67 which also support the shaft 68 whose pendant arms 69 are joined by the link 70 to the bar 71 which actuates all of the pistons 72 within the sleeves 52. The reduced outer ends 73 of the pistons 72 are preferably guided in the bracket 74, although the pistons 72 can also be operated, as shown in the somewhat diagrammatic views in Figures 2 to 5 inclusive, namely without a guide for the outer end of the piston.

A rocking movement is imparted to the shaft 68 through the slotted lever 75 whose connecting rod 76 is moved by the crank 77 on the shaft 62. It follows that the rotation of the shaft 62 first causes the port 53 to register with the opening 54 and permits the material to flow into the measuring compartment. The outward movement of the piston 72 now actually draws the material into the measuring compartment, after which the sleeve is moved to the position shown in Figure 5, permitting the material to be discharged into a receptacle beneath (not shown) under action of the piston 72, but it cannot return to the hopper 47 since the connecting ports 53 and 54 are out of register. This provides not only a rapid flow of material into the receptacle but always insures the introduction of a definite quantity of material therein, and the forced passage of material into and out of each of the measuring cylinders also insures against the stoppage of the ports by foreign matter or by partially congealed material which might find its way into the measuring chamber.

When used in the machine of our application Serial No. 153,099 above referred to, two or more of these units are employed, one to deposit hot material (chocolate) and the other to deposit cold material (ice cream).

It will be noted that a slot 75 is provided

in the lever 75 whereby the point of connection between the lever 75 and the rod 76 may be altered to vary the stroke of the rocking lever 75.

5 In order to clean the apparatus after its use has been discontinued, a suitable washing fluid may be introduced into the hopper 47 and the shaft 62 rotated sufficiently to feed out the washing material. Should it be found that the material gums up within the sleeve 52 the cover plate 50^x may be removed and the pockets 51 may be swabbed out, thus making it unnecessary to take the apparatus apart effectually to clean it.

15 What we claim is:

1. A filler for delivering a multiple of measured volumes of liquid intermittently, consisting of a hopper having a plurality of openings formed in the bottom thereof, said hopper having a base provided with a plurality of cylindrical openings each closed at one end each of which openings communicates with one of the hopper openings, each cylinder opening having a hollow sleeve open throughout its length and slidably placed therein, said sleeve having a port therein which registers with one of said hopper openings when said sleeve is in an outward position, said sleeve having a second port formed therein registering with a discharge port in said base when said sleeve is in the innermost position; a piston in each sleeve and having a piston rod; and means for sliding said piston and sleeve in a manner that said hopper opening will communicate with the interior of said sleeve while said piston is being withdrawn and that the discharge port of said sleeve shall communicate with the discharge of said base when said piston is forced into said sleeve.

40 2. A filler for delivering a multiple of measured volumes of liquid intermittently consisting of a hopper having a plurality of openings formed in the bottom thereof, said hopper having a base provided with a plurality of cylindrical openings each closed at one end each of which openings communicates with one of the hopper openings, each cylinder opening having a hollow sleeve open throughout its length and slidably placed therein, said sleeve having a port therein which registers with one of said hopper openings when said sleeve is in an outward position, said sleeve having a second port formed therein registering with a discharge port in said base when said sleeve is in the innermost position; a piston in each sleeve and having a piston rod; and means for sliding said piston and sleeve in a manner that said hopper opening will communicate with the interior of said sleeve while said piston is being withdrawn and that the discharge port of said sleeve shall communicate with the discharge of said base when said piston is forced into said sleeve, said last named means comprising a

lever pendently mounted at one side of the hopper, said lever having an arcuate slot, an operating shaft passing through said slot, a cam on said shaft, cam lobes on said lever engaging opposite sides of said cam, a connection between said lever and all said sleeves to move the same in unison, a rock shaft, a lever secured to said rock shaft, a connection between said last named lever and all said pistons whereby they move in unison, a crank on said operating shaft, a connecting rod and rocking lever connection between said crank and said rock shaft and including means to adjust the stroke of the rocking lever.

45 3. A filler for delivering a multiple of measured volumes of liquid intermittently consisting of a hopper having a plurality of openings formed in the bottom thereof, said hopper having a base provided with a plurality of cylindrical openings each closed at one end each of which openings communicates with one of the hopper openings, each cylinder opening having a hollow sleeve open throughout its length and slidably placed therein, said sleeve having a port therein which registers with one of said hopper openings when said sleeve is in an outward position, said sleeve having a second port formed therein registering with a discharge port in said base when said sleeve is in the innermost position; a piston in each sleeve and having a piston rod; and means for sliding said piston and sleeve in a manner that said hopper opening will communicate with the interior of said sleeve while said piston is being withdrawn and that the discharge port of said sleeve shall communicate with the discharge of said base when said piston is forced into said sleeve, said last named means comprising a lever pendently mounted at one side of the hopper, said lever having an arcuate slot, an operating shaft passing through said slot, a cam on said shaft, cam lobes on said lever engaging opposite sides of said cam, a connection between said lever and all said sleeves to move the same in unison, a rock shaft, a lever secured to said rock shaft, a connection between said last named lever and all said pistons whereby they move in unison, a crank on said operating shaft, a connecting rod and rocking lever connection between said crank and said rock shaft and including means to adjust the stroke of the rocking lever, a supporting frame for the hopper in which said operating shaft, said rock shaft and the support for said pendent levers are mounted, said frame including a transverse portion having guides for the rods of said pistons.

50 4. In a filling machine, a hopper with a discharging opening and a base provided with a cylindrical chamber passing horizontally through the same, a cover plate over one end of said chamber, a sleeve valve open at both ends and fitted slidably in said chamber, said base having a discharge opening, said

sleeve valve having ports to register alternately with said openings, a piston slidably mounted in said sleeve valve and having a rod projecting out the open end of said chamber and valve, a pendently supporting lever connected to said sleeve valve, a rock shaft, a lever on said rock shaft, link connected to said piston's rods, an operating shaft, a crank, pitman and lever connection between said operating shaft and said rock shaft, a cam on said operating shaft and cam lobes on said pendently levers associated with said cam, all being arranged whereby said hopper opening will communicate with the interior of said sleeve while said piston is being withdrawn ¹⁵ and the discharge port of said sleeve will communicate with the discharge of said base when said piston is forced into said sleeve, substantially as shown and for the purposes described.

WILSON R. MYERS.
